UNITED STATES PATENT OFFICE.

CHARLES E. SCRIBNER, OF JERICHO, VERMONT, ASSIGNOR TO WESTERN ELECTRIC COMPANY, OF CHICAGO, ILLINOIS, A CORPORATION OF ILLINOIS.

PROTECTIVE APPARATUS FOR RAILWAY TELEPHONE SETS.

No. 834,764.

Specification of Letters Patent.

Patented Oct. 30, 1906.

Application filed October 21, 1904. Serial No. 229,470.

To all whom it may concern:

Be it known that I, CHARLES E. SCRIBNER, a citizen of the United States, residing at Jericho, in the county of Chittenden and State of Vermont, have invented a certain new and useful Improvement in Protective Apparatus for Railway Telephone Sets, of which the following is a full, clear, concise, and exact description.

10 My invention relates to electrical apparatus, such as telephone sets, and has for its object to provide improved means for controlling the operative condition thereof and for protecting the user of such apparatus 15 from abnormal currents with which the line conductors leading thereto may be accidentally charged.

It is customary at the present time to provide telephone-lines in association with electric railways, and telephone sets are located at intervals, to be used in communicating with the dispatcher who controls the movements of the cars and in reporting trouble or accident on the line. Telephone-lines of this 25 character, being associated with the power-transmission circuits of the road, are particularly subject to high-potential crosses, and when such a cross exists the use of the telephone sets connected with the line is attended by considerable danger to the user. It is therefore necessary in the case of such lines to make especial provision for the protection from abnormal currents of the parts of the associated telephone sets with which 30 the user is liable to come into contact, and it is mainly toward meeting this requirement that my invention is directed.

One feature of my invention consists in means actuated in obtaining access to the 40 containing-case of the apparatus for rendering operative a protective or safety device which before the user has had an opportunity to touch any of the parts within the case will act to prevent any abnormal current that may exist on the line from being communicated to the apparatus. I preferably employ fuses in connection with the safety appliance referred to which are included in the circuit of the apparatus, said 45 circuit being arranged to be closed as the door of the containing-case is opened, so that if abnormal currents are present in the line

the fuses will blow while the door is being opened, and thus constituting a signal whereby the person desiring to use the instrument is 55 apprised of the abnormal and dangerous condition of the line. I also preferably provide in association with the fuses a safety appliance of a different character, such as a lightning - arrester, to coöperate with the 60 first-mentioned protective device in the protection of the apparatus and safeguarding of the user.

Another feature of my invention lies in mounting the protective apparatus and the 65 telephone apparatus of the set in separate groups with a grounded metallic shield between them, so that any dangerous high-potential condition that may exist in the compartment wherein the protective devices 70 are mounted may not be communicated to the telephone apparatus, but may instead be diverted through the grounded shield interposed between the two groups.

Another feature consists in improved 75 means actuated in closing the containing-case of the instrument for automatically disconnecting the set from the line and opening its local circuit to guard the apparatus from dangers from external sources, such as abnormal currents, and also to avoid waste of 80 current when the device is not in use.

I will describe my invention more particularly by reference to the accompanying drawings, which illustrate a telephone set 85 equipped in accordance with my invention, and the particular parts, improvements, or combinations which I regard as novel will be pointed out in the appended claims.

Figure 1 is a front view of the containing- 90 case of a telephone set embodying my invention with the door of the case opened. Fig. 2 is a vertical sectional view on line 2 2 of Fig. 1. Fig. 3 is a transverse sectional view of the containing-case on line 3 3 of 95 Fig. 1, and Fig. 4 is a diagrammatic view of the circuits of the telephone set to illustrate the application of my invention thereto.

The same letters of reference are used to designate the same parts in each of the 100 figures of the drawings.

The telephone set comprises a case *a*, within which is mounted the usual telephone apparatus, the case having a door *a'* adapted to

opening and closing to effect the connection and disconnection of the apparatus of the set with the circuit with which it may be associated.

5 Two pairs of switch-springs b b' and c c' controlling the circuit connections of the apparatus are arranged to be actuated in the movement of the door a' of the case and are provided with a supporting-bracket c^2 , which 10 may be carried by an upright plate b^4 , mounted upon the removable shelf b^4 . The said springs may be provided with a plunger d , supported by the bracket c^2 and adapted to be moved by the door of the case as it is 15 closed to permit said springs b c to separate from their anvils b' c' , respectively. The plunger may carry a cam d' , which, when the door is closed, lies out of engagement with said springs which rest out of contact with 20 their anvils, to maintain the apparatus disconnected from the line. A helical spring d^2 may serve to move the plunger upon the opening of the door to cause the cam d' to engage said springs and close the same upon 25 their respective anvils to complete the circuit connections of the apparatus with the line. I preferably provide a lug e upon the inner surface of the door adapted to engage the plunger d as the door is closed to operate 30 the same. The anvils b' c' of said controlling-springs may be connected with the apparatus of the set, while the springs b c are connected with fuses f f' , electrically united with the line-wires. The fuses may be mounted 35 in clips g g' and g^2 g^3 , respectively, secured to a suitable insulating-block h . The terminal clips g g^2 are electrically connected with switch-fingers k k' , respectively, carried by the insulating-block h . The fingers k k' are 40 adapted when the shelf b^4 is in its normal position within the containing-case to engage switch-springs l l' , which are mounted upon but insulated from the wall of the containing-case and which form the terminals of the 45 line-wires leading to the instrument.

As the door of the case is opened the spring d^2 moves the plunger d to close the springs b c against their anvils b' c' , thereby connecting the telephone set to the line with 50 the fuses interposed between said apparatus and the line-wires. In case abnormal currents are present in the line the fuses will be blown before the person desiring to use the telephone has an opportunity to grasp the 55 telephone instrument T , thereby protecting him from injury and apprising him of the condition of the apparatus.

A second safety appliance is preferably interposed between the fuses and the apparatus 60 of the set which may comprise a pair of lightning-arresters m m' , whose line-plates are connected with opposite sides of the circuit and the remaining plates connected with the grounded frame of the case, so that 65 abnormal current in the line will be diverted

to earth through the arresters and blow the fuses when the case is opened.

I preferably provide a pair of springs o o' , which may be included in the local transmitter-circuit to control the operative condition thereof. Said springs may have a supporting-bracket v^2 therefor and a plunger p adapted to be moved by the door of the case for operating said springs. The plunger is reciprocally mounted in said bracket and carries a cam p' , which when the plunger is moved by the door in closing occupies a position out of engagement with said springs, which are then separated to open the circuit of the transmitter. When the door is opened, a spring p^2 serves to move the plunger to cause said cam to close the springs and complete the circuit for the transmitter. A lug p^3 is preferably carried upon the inner surface of said door to operate the plunger p upon the closure of said door.

When the door is closed, the plungers d p are moved to cause their associated cams to effect the separation of the several switch-springs from their anvils, thereby disconnecting the telephone set from the line to guard the apparatus against disturbances in the line and also to prevent useless consumption of current in the local circuit of the transmitter.

It will be noted that the protective devices, including the fuses f f' and the carbon plate-arresters m m' and the switch controlling their connection with the line, are mounted together on the shelf b^4 , so that the upright metallic plate or partition b^3 is interposed between them and the generator and the switch o o' that controls the local circuit of the set, while the metallic body of the shelf itself is interposed between them and the telephone instrument. As the shelf and its partition are connected to the earth they serve as a shield to prevent any dangerous current condition that may exist in the protective-device compartment from being communicated to the telephone apparatus in the other compartments.

I claim—

1. The combination with electrical apparatus, of a containing-case therefor, a circuit for said apparatus, switching mechanism for controlling said circuit, means actuated in opening said case for operating said switching mechanism to close the circuit, and means automatically operated upon the closure of said circuit by abnormal current therein, for opening the circuit and dissipating said abnormal current.

2. The combination with electrical apparatus, of a containing-case therefor, a circuit for said apparatus, switches controlling said circuit, fuses in the circuit, and means actuated in opening the case adapted to close said switches; whereby if abnormal currents are present in the circuit the fuses will be blown.

as the case is opened, and the person attempting to use the apparatus protected.

3. The combination with electrical apparatus, of a containing-case therefor, a door for said case, a circuit for the apparatus, switches controlling said circuit, fuses in the circuit, plungers for operating said switches, and means actuated in opening said door for moving said plungers to close said switches; whereby if abnormal currents are present in the circuit the fuses will be blown as the door is opened, and the person attempting to use the apparatus protected.

4. The combination with a telephone set, of a containing-case therefor, a door for said case, a telephone-line with which said set is associated, switches controlling the connection of said set with the line, fuses in the circuit controlled by said switches, said switches being adapted to be opened by the door when it is closed, and means actuated in opening said door, adapted to close said switches; whereby if abnormal currents are present in the line, due to a cross with said high-tension circuit, the fuses will be blown as the door is opened, thereby protecting the person attempting to use the set.

5. The combination with a telephone set, of a containing-case therefor, a door for said case, a telephone-line with which said set is associated, switch-springs controlling the connection of said set with the line, fuses in the circuit controlled by said switch-springs, plungers controlling said switch-springs, said door being adapted upon the closure thereof to move said plungers to open the switch-springs, and springs actuated in the opening of said door, to move said plungers to close said springs; whereby if abnormal currents are present in the line, the fuses will be blown as the door is opened, thereby protecting the person attempting to use the telephone.

6. The combination with a telephone set, of a containing-case therefor, a door for said case, a circuit for said set, switches controlling said circuit, fuses in said circuit, a lightning-arrester connected from the circuit between the fuses and the telephone apparatus to ground, and means actuated in opening said door for closing said switches; whereby abnormal currents in the circuit will be diverted to earth through the arrester as said

door is opened in case the fuses are not blown or an arc is formed therein.

7. The combination with electrical mechanism, of a containing-case therefor, a door for said case, switch-springs controlling the circuits of said mechanism, plungers mounted within the case for said switch-springs, the door of the case being adapted when the same is closed to engage and move said plungers to separate said switch-springs, and springs for said plungers adapted when said door is opened to move the plungers to close said switch-springs.

8. The combination with a telephone set, of a containing-case therefor, a door for said case, switch-springs controlling the circuits of said telephone set, one set of said springs being included in the local transmitter-circuit, the remaining sets of switch-springs being included in the portion of the circuit connected with the line, plungers for operating said switch-springs, the inner face of the door of the case adapted when the same is closed to move said plungers to separate said switch-springs, and springs adapted when the door is opened to move said plungers to close the switch-springs.

9. In a telephone set the combination with the telephone apparatus of a protective appliance therefor, and a metallic mounting having a part thereof interposed as a shield between said telephone apparatus and protective appliance, said part being grounded, whereby dangerous currents may be diverted from said telephone apparatus.

10. The combination with electrical mechanism, of a containing-case therefor, a door for said case, switch-springs controlling the circuits of said mechanism, plungers mounted within the case, cams carried by said plungers adapted to operate said springs, the door of said case being adapted when closed to engage said plungers and cause said cams to separate said springs, and springs for said plungers adapted when the door is opened to move the plungers to effect the closure of said switch-springs.

In witness whereof I hereunto subscribe my name this 19th day of August, A. D. 1904.

CHARLES E. SCRIBNER.
